UNITED STATES PATENT OFFICE.

EDWARD E. CLEMENT, OF WASHINGTON, DISTRICT OF COLUMBIA, ASSIGNOR, BY MESNE
ASSIGNMENTS, TO JAMES R. GARFIELD, TRUSTEE, OF CLEVELAND, OHIO.

TELEPHONE-EXCHANGE SYSTEM.

1,210,604.

Specification of Letters Patent.

Patented Jan. 2, 1917.

Application filed July 12, 1912. Serial No. 709,097.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention pertains to telephone exchange systems and is especially applicable to automatic and semi-automatic connective systems therefor.

An object of my invention is to provide a 15 novel arrangement of circuits and apparatus whereby subscribers' lines are interconnected by means of power driven switches instead of the usual impulse driven switches, thereby doing away with the necessity of 20 an impulse sending machine.

Another object is to provide a novel 25 method of control for power driven switches whereby they may subserve the functions of so-called selector and connector switches.

26 A further object of my invention is to provide a unidirectional power driven switch of novel construction for interconnecting subscribers' line circuits with controlling means therefor separate from the 30 driving means, and to so construct such a switch that it may be used either as a normally active or inactive switch and can be readily changed from one type to the other.

Other objects and advantages will be hereinafter set forth in detail.

Generally stated, the invention comprises a telephone exchange system in which the line circuits are interconnected by means of power driven switches, and a novel method 40 of controlling the movements of said switches by means of impulses sent from the switches to the controlling means, whereby the use of a sending machine is obviated.

My invention is illustrated in the accompanying drawings in which:

45 Figures 1, 2 and 3 are respectively front, side and top plan views of a power driven switch comprising a group of ten switching elements. Figs. 4 and 5 are detail views of 50 one of the switching elements. Fig. 6 shows subscribers' line circuits terminating in contacts of power driven primary selector switches. Fig. 7 is a power driven first selector switch and its associated trunk and 55 circuits. Fig. 8 is a power driven connector

switch and its associated trunk and circuits. Fig. 9 is a power driven secondary selector and associated circuit. Fig. 10 is a diagram of the apparatus and circuits constituting the switch controlling device. Fig. 11 is a 60 four party line circuit and terminal apparatus. Figs. 12, 13 and 14 illustrate a portion of an embodiment of my invention in which the primary and secondary selection is effected through two-motion step by step 65 switches, and are to be used in place of Figs. 6, 7 and 9.

Referring to Figs. 1 to 5, the power driven switch here shown consists of a group of ten switching elements driven by a common 70 shaft, each element being controlled by an individual magnetically operated clutch. The switching elements consist of a contact bank 500 containing pairs of contacts such as 501, 502 and 503 arranged in vertical 75 groups (Figs. 4 and 5), and the groups arranged in an arc so as to be successively engaged by the wipers 504. The wipers 504 are bridging wipers, adapted to bridge or form a shunt across each of the pairs of 80 contacts of a group. There are two groups of bridging wipers 504 set 180 degrees apart. They are rotated by a common, constantly 85 rotating shaft 540, and their movements controlled by a clutch member 505 operated upon by an electromagnet 506. The contact banks 500 are secured to standards 507 and 508 by means of the binding plates 510 and nuts 511, and to the rear standard 509 by means of a bracket 512 and nuts 513. The 90 end of the bracket 512 is preferably forked to facilitate assembling and the ends of the binding plates 510 may also be forked for the same reason. The standards 507, 508 and 509 are rigidly secured at top and 95 bottom in triangular castings 514 and 515 and extend through the lower casting sufficiently to afford attachment of a third casting 516. A rotatable shaft 540 is mounted 100 in bearings 517, 518 and 519 in the castings (see Fig. 1), the lower bearing 519 being preferably a thrust, ball bearing. The shaft 540 is adapted to be driven by power transmitted from a counter-shaft 520 through the usual bevel gears and a worm gear 521- 105 522. Arranged at intervals along the shaft are clutch collars 523, one for each switching element, rigidly fixed to the shaft by means of set screws or the like. A split hub 524 carrying the wiper arm 525, fits loosely on 110

BEST AVAILABLE COP

1,210,604

the shaft and bears upon the upper surface of the clutch collar. At either side of the hub are clutching pawls 505 pivoted at their upper ends to the hub and adapted to fall 5 into a notch 526 in the clutch collar 523. The pawls 505 extend downwardly beyond the clutch collar and are bent outward at an angle as shown in the lower switching element in Fig. 2. Below the clutch collar 10 is an annular platform or rim 541 formed with a sleeve 527 fitting loosely on the shaft 540 and bearing on the upper surface of an abutment ring 528 fixed rigidly to the shaft. The periphery of the rim 541 is rounded or 15 beveled and the upper surface of the rim is provided with a brake pad of leather or the like. The rim 541 is adapted to reciprocate vertically on the shaft 540, between the abutment ring 528 and the clutch collar 523, by 20 the energization and deenergization of an electromagnet 506. Motion is transmitted to the rim 541 from the armature 543, of the magnet 503, by means of the armature lever 542, and the armature and lever are restored 25 to normal position as shown by retractile springs 544. Each clutch magnet 506 is held firmly in its place on the switch by a cast yoke 529 upon which it is rigidly mounted by means of screws 530, the yoke 30 being clamped at each end to the standards 507 and 508 by means of forked clamps 531 and set-screws 532. The split hub 524 is formed with flanges 535 and 536 spaced apart to receive between them the wiper 35 arm 525 which is recessed in the center, so that it can slide between said flanges and straddle the hub. One half of the split hub has a flat key-way 536 milled in the flanges to receive a key 537 which passes through 40 notches 538 in the sides of the recess in the wiper arm, said key being held in place by a set screw 545 threaded in the key and bearing against the hub. The wiper arm 525 and the key 537 thus hold the hub together. When the switch is used as a constantly rotating primary or secondary selector, the clutch magnet is arranged as 45 shown, namely, to allow the clutch members to normally engage and to disengage them and stop the wiper arm upon energization. Also, when used as a constantly rotating switch, the contacts and wipers are so arranged that as soon as one set of wipers passes off the last group of contacts the other 50 set will engage the first group, as shown in Fig. 4.

When the switch is used as a normally inactive switch such as a selector or connector, it is necessary that it have a normal or zero 55 position and so in such cases the contacts are arranged so that when the wiper arm 525 is in the position shown in Fig. 4 the wipers will be clear of all contacts. Also when used as a selector or connector it is necessary 60 to provide a set of off normal contact

springs, as shown at 533 in Fig. 4, consisting of a bank of contact springs mounted on the yoke 529 and adapted to be actuated by either one of the studs 534 carried by the wiper arm 525. It is further to be noted that when used as a normally inactive switch, the clutch magnet is arranged so as to allow the clutch members to remain normally out of engagement and to cause them to engage upon energization, as shown 70 in diagram in Fig. 7.

All the switches may be equipped with a bank of off-normal contact springs 533 and studs 534 so that the only alteration necessary in changing from a continuously actuated switch to a normally inactive switch 80 would be to wire the off-normal springs and reverse the operation of the clutch magnet. In mounting the moving parts of the several switching elements, the clutch collars 523 are 85 set on the shaft with the notches 526 of the different collars arranged at different angles so that when their associated wiper arms are in motion they will be spaced apart at corresponding angles as shown in Fig. 3 thus 90 preventing any two sets of wipers from engaging the same multiples at the same time. With this arrangement wiring is facilitated inasmuch as the contacts of a group of 95 switching elements may be multiplied vertically instead of staggering.

It will be seen from the foregoing, that any one or more of the switching units may be assembled or taken apart without disturbing the other units.

In Fig. 6 three substations are shown whose line wires 1 and 2 terminate in the central office in contacts of a cut-off relay R^2 and are normally connected through back contacts of said relay to the battery B 100 through a line relay R^1 . The line wires 1 and 2 of each line are adapted to be connected through front contacts of the cut-off relay R^2 to extensions 3 and 4 respectively, terminating in multiple contacts in the 105 banks of primary selector switches such as S^1 . The line relay R^1 is adapted when energized to connect ground to its associated multiple test contacts 549 in the primary selectors such as S^1 . The primary selectors 110 are provided with clutch magnets such as M^{23} which normally allow the wipers to rotate and upon energization operate to disengage the clutch members and bring the wipers to rest. The contacts 549, 551 and 115 553 are normally open and when bridged or shunted by their respective wipers 550, 552 and 554 connect the extensions 3-4 and the test circuit 559 to the conductors 5, 6 and 557 respectively.

In Fig. 7, the trunk conductors 5 and 6 extend from the primary selector switch S^1 by way of conductors 595 and 597 respectively through normally open contacts of a control relay R^{53} to tip and sleeve battery 120 125 130

supply relays R^{14} and R^{15} respectively. The trunk conductors 5 and 6 are also extended in multiple through condensers C^1 — C^2 and normally closed contacts of a trunk cut-off relay R^{42} to contacts 560 and 561, respectively, in the first selector switch S^4 . Control relay R^{53} is connected in multiple with the clutch magnet M^{23} (Fig. 6) and both are energized over a common circuit including the wire 558, normally closed contacts of relays R^{54} and R^{15} , and wire 557 leading to the test contacts of S^4 (Fig. 6). Trunk cut-off relay R^{42} is partially controlled through a front contact on R^{15} and partly over a wire 107 leading to the operator's circuit. Relays R^{54} and R^{55} are release relays for the primary selector switch S^4 and first selector S^5 , respectively. The first selector switch S^5 is the same as S^4 except that it has four sets of contacts in its banks and is adapted to assume a normal or zero position as shown in the drawing and to be rotated upon the actuation of its clutch magnet M^{24} . Off-normal springs 567, 568 and 569 connect one terminal of relay R^{41} to ground through wire 570 when the switch S^5 is at normal; and when the switch is off-normal, they open the first connection and connect ground to the release relays R^{54} and R^{55} by way of a back contact on tip relay R^{14} and wire 571. Relay R^{41} is initially energized through a front contact of relay R^{42} and off-normal spring contacts 568—569, and locks itself to ground through a front contact wire 147 and a back contact of relay R^{20} by way of conductor 593. Lamp L^5 is an off-normal signal lamp and is caused to glow as long as the switch S^5 is out of its normal position, its circuit being completed to ground through contact springs 567—568. Relays R^{20} and R^{21} are the switch control relays and directly control the clutch magnet M^{24} .

In the contact bank of switch S^5 , the upper row of contacts 572 have their upper member connected in multiple to wire 573 connecting with one terminal of relay R^{21} , and their lower members connected to battery through battery lead 574. Conductors 573 and 574 are bridged by a resistance r^2 . The contacts 572 are so spaced apart that as the bridging wiper 575 passes from one contact to the succeeding contact the shunt around resistance r^2 through the contacts is momentarily removed. In the second row of contacts, the lower members are connected in multiple to wire 147 while the upper members constitute multiple terminals of different test wires such as 200 leading to connector switches.

In the third and fourth rows of contacts 561 and 560, the lower members of the respective rows are connected in multiple to trunk conductors 9 and 10 while the upper members constitute multiple terminals of different connector trunks such as 15 and 16.

Referring to Fig. 8, the connector switch S^6 is the same in structure and operation as S^5 except that the off-normal contact springs are more numerous and the test contacts are omitted. The first row of contacts is connected to form ten groups of ten, the first contacts 577 of all the groups having their upper and lower members connected in multiple to the conductors 580 and 581, respectively, while the remaining contacts 577^a of all the groups have their upper and lower members connected in multiple to the conductors 580 and 581^a respectively, the conductor 581^a leading to a front contact on the relay R^{57} . A resistance r^3 is bridged between the conductors 580—581. The bridging wipers 582, in passing over the contacts 577 and 577^a, alternately close and open the shunt around the resistance in the same manner as that of S^5 . The contact rows 578 and 579 have their lower members connected in multiple to the trunk conductors 18 and 17 respectively, while their upper members constitute multiple terminals of different substation lines such as 255 and 254, respectively. Trunk conductors 17—18 are connected through front contacts on relay R^{26} to conductors 15—16 which terminate in multiple contacts 560—561 (Fig. 7) of different first selector switches such as S^5 . Relays R^{25} and R^{26} supply current to the called line through their windings. R^{25} also controls the release circuit and R^{26} acts as a trunk cut-off relay. R^{22} and R^{23} are the switch control relays reciprocally controlling and controlled by the switch S^6 . R^{23} also controls the switch S^7 by means of a stepping magnet M^{11} acting as a repeating relay to step the switch S^7 around so as to pick out generator current of the proper character. Operation of relay R^{23} closes the circuit of R^{24} whose locking contact r^{241} is connected to the back contact of relay R^{22} . R^{23} also closes circuit of R^{27} . This latter remains energized until the called party answers or until the calling party hangs up his receiver.

In case the called party is busy, relay R^{27} will be deenergized by action of test relay R^{29} . Relays R^{24} , R^{27} and R^{29} all have their circuits completed to the grounded side of battery through test wire 200, contacts 576, conductor 147, 593, and back contact of relay R^{20} to ground.

Relay R^{57} is adapted to normally connect the conductors 580—581 to conductors 583—584 respectively and upon energization, to open this connection and connect conductors 580—581 to conductors 585—586 respectively, and also to connect conductor 581^a to conductor 585. The energization of R^{57} also removes a shunt from conductors 585—586 at r^{572} , and completes the energizing circuit of R^{58} at normally open contact r^{573} .

Relay R^{58} is a self locking relay and its function is to open the controlling circuit 240 between relay R^{22} and clutch magnet M^{25} upon the secondary movement of the 5 connector switch S^8 .

The switch S^7 restores by continuing its motion until the wiper ws^{700} disengages the contacts s^{700} and assumes the normal or zero position as shown. The wiper ws^7 just before reaching normal position connects the free side of battery to the release relay R^{56} by way of contact $9s^7$ and conductor 269. The switch S^7 continues to rotate to its normal position after the called party hangs up 10 his receiver, thus providing a slow release after connection.

Relay R^{28} is a ringing relay adapted to be intermittently energized through an interrupter I^2 . B^2 is a busy back circuit which 20 is connected to one side of the calling line whenever the called line tests busy.

In Fig. 9 is shown a power driven secondary selector switch S^8 which is identical in its operation to the primary selector switch 25 S^4 (Fig. 6). The switch S^8 (Fig. 9) has four rows of contacts in its bank. The test contacts 587 have their upper members connected in multiple to one terminal of relay R^{59} and their lower members connected each 30 through a conductor such as 45 to a front contact on the control relay of a primary selector (Fig. 7). In the row of contacts 588 (Fig. 9) the upper members are connected in multiple to conductor 109 and the 35 lower members are connected separately to wires such as 107 leading to the trunk cut-off relays such as R^{42} of Fig. 7. In the row 589 the upper members are connected in multiple to the tip conductor 131 of the operator's control circuit and the lower members 40 are connected separately to the tip control wires such as 130 leading to the first selector circuit. In the row 590 the lower members are connected in multiple to the 45 sleeve conductor 132 and the upper members are connected separately to sleeve control wires such as 135 leading to the first selector switches. Relay R^{59} is a control relay energized when the switch S^8 engages the 50 contacts associated with a calling primary selector and actuates to close the circuit of the clutch magnet M^{26} , and to partly close the circuit of listening relay R^{33} . The calling relay R^{34} is also energized when the switch 55 S^8 engages the contacts associated with a calling primary selector and actuates the calling signals such as N , the calling lamp L^5 (Fig. 10) and the meter E . Listening relay R^{33} operates to connect the operator's 60 listening set OR across the trunk 131-132 in the usual manner. R^{36} is the starting relay and is energized in series with R^{42} (Fig. 7) by the closure of key SK (Fig. 10). The 65 actuation of R^{36} completes the circuit of the stepping magnet M^{16} and closes the circuit

of guard lamp L^2 (Fig. 10) and disconnects battery from the first five contacts in the lower bank of switch S^3 . S^3 is the operator's control switch stepped around by the magnet M^{15} and operates to distribute the 70 circuit connections between the operator's control circuit (Fig. 9) and a switch control circuit (Fig. 10). The switch S^3 is restored in a manner similar to that of the switch S^7 by a circuit closed through the magnet M^{15} 75 and interrupter I upon the actuation of relay R^{33} . Just before the switch S^3 reaches its normal position a cam on the spindle operates to momentarily close the contacts 167-168 which completes the circuit of release relay R^{60} of the switch S^8 . Relay R^{37} is the trunk starting relay and is also used for release in case the calling subscriber has hung up his receiver or if the operator fails to get a response on operating the listening 80 key. R^{38} controls the connection of a tone test signal to the operator's listening circuit.

Referring to Fig. 10, number one key of each strip is connected to the first contact d^1 80 on the impulse receiver S^{14} which takes one step at each impulse sent back from the switches; number two key to the second contact d^2 , and so on to number ten key which is connected to the tenth contact d^{10} . Each strip 95 of keys has a common wire connected to one contact of each key in the strip and leading to its proper contact in one or the other of the controlling banks associated with switch S^3 . The order in which these are arranged 100 to transmit impulses in proper sequence is as follows: At the first rotation of the impulse receiver the first strip of keys K^1 (hundreds) is connected to the tip side of the trunk; second rotation, ten test impulses to 105 impulse receiver over sleeve side of trunk; third rotation, selective ringing strip K^4 connected to tip side of trunk; fourth rotation, keys K^2 (tens) connected to sleeve side; fifth rotation, keys K^3 (units) connected to 110 tip side of trunk; during the fifth rotation and just after the units impulses have been sent, a single test impulse is sent to sleeve side of trunk; after the fifth rotation, arm ws^{300} engages contacts connected to battery 115 energizing relay R^{33} . This relay unlocks R^{36} restores switches S^3 and S^8 , thus disconnecting secondary switch S^8 from the primary trunk.

In Fig. 11 is shown a four party line to 120 which are connected to the substations A^1 , A^2 , etc., and which terminates in the central office in contacts of the cut-off relay R^{43} through which it is normally connected to the usual line relay. The extensions 254-255 125 terminate in multiple contacts of connector switches such as S^8 (Fig. 8).

Figs. 12, 13 and 14 are similar to Figs. 6, 7, 8 and 9 except that the primary and secondary selection is accomplished by the use 130

of two-motion step by step switches instead of the single motion power driven switch. Figs. 12, 13 and 14 are to be substituted for Figs. 6, 7, 8 and 9 to show a complete commercial embodiment of my invention.

Referring to Fig. 12, each line circuit 1—2 is provided with a line relay R' and a cut-off relay R^2 which when energized disconnects the line relay R' and connects the tip 10 and sleeve sides of the line to its multiple bank contacts in the primary and connector switches of its group. The attraction of the armature r^{12} of the relay R' connects ground to the individual test contacts of the primary 15 switches S^4 . The attraction of armature r^{11} locks the relay R' on short circuit to ground through armature r^{23} of relay R^2 , which prevents interference by the subscriber in case he should move his receiver 20 hook. The line relays R' are divided into groups of ten and the windings of each group are connected in multiple to the winding of a relay R^3 common to the group, which when energized connects ground to 25 the row contact of the primary switch through the armature r^{31} , thus designating the group of lines calling, while the relay R' designates the particular line in the group. Associated with each primary distributing 30 switch S there is a secondary distributing switch S^2 , and a kick-off switch S' . The function of the secondary distributing switch is to pick out an idle operator's circuit and start the same to testing for the 35 group of primary trunks over which the call originates. This can be done because there being only one switch S^2 for each group of one hundred lines, that is to say for each group of ten trunks such as shown in Fig. 40 13, and since it is convenient to arrange the contacts of each group of ten trunks in one and the same row in the secondary selector switches S^8 (Fig. 14), each secondary distributing switch can therefore be directly 45 identified with its own associated row of primary trunk contacts in each of the secondary selector switches.

Referring to Fig. 13, the relay R^{12} is the row test relay, and is energized when the wiper w^{26} finds an active contact, disconnects rotary relay R^{18} and in its place connects vertical relay R^{19} . The relay R^{15} is used in testing for the individual contact as well as a battery supply relay for the calling subscriber. When energized this relay disconnects the row relay R^{12} . The deenergizing of relay R^{12} disconnects the relay R^{15} from the test wiper w^{25} and connects it to the 55 sleeve wiper w^4 in series with the cut-off relay R^2 . Relay R^{14} is the tip battery supply relay and controls the release magnets M^3 and R^{55} after the first selector switch S^5 has moved off-normal. The relay R^{42} is used for opening the talking circuit while the impulses 60 are being sent to operate the outgoing 65

switches. This relay also with R^{15} jointly controls the relay R^{13} . Relay R^{41} is the test relay having its locking contact r^{413} connected to the test wire 147. Its circuit is initially closed through a front contact of 70 relay R^{42} .

Referring to Fig. 14 relay R^{31} is the row test relay and R^{30} the individual test relay. Relay R^{32} is the control relay and corresponds to relay R^{13} (Fig. 13). Relay R^{34} is 75 the signal relay and pulls up in series with relay R^{42} (Fig. 13) after the primary trunk has found the line and the secondary switch S^8 has found the trunk.

The operation of the system shown in 20 Figs. 6, 7, 8, 9 and 10 is as follows: Subscriber at substation A upon lifting his receiver closes his line circuit energizing the line relay R' by current from battery B through R' , back contact of cut-off relay R^2 , line wire 1 through circuits of substation A' back over line wire 2 and to ground by way of back contact of the cut-off relay. Relay R' upon actuation connects the battery through a front contact to wire 559 leading to the test contact 549, and when the wiper 550 of the continuously rotating switch S^4 engages and bridges or closes the contact members 549, the circuit of control relay R^{53} and clutch magnet M^{23} is completed over the following path: battery B, contact of R' , 559, contact 549, 557 into Fig. 7, normally closed contact of sleeve relay R^{15} , 591, normally closed contact of release relay R^{54} , 558, to ground through relay R^{52} and clutch magnet M^{23} in multiple. M^{23} upon actuation disengages the clutch members of switch S^4 causing the switch to come to rest with its wipers 550, 552 and 554 in engagement with the contacts 549, 551 and 553 respectively. The closure of contacts 551 and 553 connects the extensions 3—4 with the trunk 5—6. Relay R^{53} upon actuation connects battery to wire 45 and connects one terminal each of tip and sleeve relays R^{14} and R^{15} to the tip and sleeve trunk conductors 5 and 6 by way of wires 594—595 and 596—597, respectively.

Current now flows from battery B (Fig. 7) through R^{15} , 596, contact of R^{53} , 597, sleeve conductor 6 into Fig. 6, 553, 4, R^2 to ground, energizing relays R^{15} and R^2 . R^2 upon actuation completes the circuit of tip relay R^{14} in series with R^{15} and the line circuit, which circuit may be traced as follows: battery B (Fig. 7) through R^{15} to extension 4 (Fig. 6), as above traced, and thence through lower armature of R^2 , line wire 2, substation A', line wire 1, upper armature of R^2 , extension 3, contact 551, tip conductor 5 into Fig. 7, 595, contact of R^{53} , 594 to ground through R^{14} . The actuation of relay R^{15} (Fig. 7) connects battery to wire 591 direct and opens the contact between 591 and 557 thus connecting the clutch magnet M^{23} and 125

control relay R^{53} to battery by way of wire 558, normally closed contact of R^{54} , 591 and armature of R^{15} to battery B, as long as the line circuit remains closed. Actuation of R^{15} also connects battery through armature r^{151} , wire 63 and 106 to one terminal of the trunk cut-off relay R^{42} . Switch S^8 (Fig. 9) in rotating brings its wipers into engagement with contacts 587, 588, 589 and 590, whereupon the closure of contacts 587 completes the energizing circuit of control relay R^{50} over the following path: B, (Fig. 7), through front contact of R^{53} , 45, into Fig. 9, contact 587, 597, R^{50} , 75, through springs 74-73 of operator's jack J to ground. Relay R^{50} upon actuation closes the circuit of clutch magnet M^{26} to battery and completes the circuit of relays R^{34} and R^{42} (Fig. 7) in series from ground through grounded contact of R^{59} , 116, r^{352} , 115, r^{361} , 114, r^{331} , 113, R^{34} , 112, 111, r^{351} , 109, contact 588, 107, into Fig. 7, R^{42} , 106, 63, r^{151} to battery. The relay R^{34} becoming energized closes circuit of night alarm N 25 through; B, 86, 110, 117, 118, r^{341} , 119, N to ground; closes circuit of guard lamp L^2 (Fig. 10) through B, (Fig. 9), 86, 110, 117, 118, r^{342} , 120, 121, into Fig. 10, L^2 , to ground; closes circuit of service meter E 30 (Fig. 9) through B, armature r^{343} , 122, 242 and magnet of service meter E to ground; and a line lamp L^3 (Fig. 10) through B (Fig. 9), r^{343} , 122, 123, into Fig. 10, L^3 to ground. The operator perceiving the signal, depresses listening key LK (Fig. 10) energizing listening relay R^{33} (Fig. 9) through: B, contact of R^{59} , 598, R^{33} , 125, into Fig. 10, contacts of key LK, 126 to ground. Relay R^{33} energizing, opens series 35 circuit of relays R^{34} and R^{42} at r^{331} and locks itself to ground through r^{331} and 114 as previously traced. Relay R^{42} deenergizing opens circuit of relay R^{41} at r^{421} . Relay R^{33} also completes the operator's 40 listening circuit as follows: receiver OR, 127, plug tip p , spring j , 128, r^{333} , 129, 131, contacts 589, 130, into Fig. 7, normally closed contact R^{41} , 133, 9, contact of R^{42} 7, condenser C^1 , 5 into Fig. 6, contact 551, 55 through substation A' and back by way of contact 553, 6, into Fig. 7, condenser C^2 , 8, contact of R^{42} , 10, 184, normally closed contact of R^{41} , 135 into Fig. 9, contact 590, 132, 136, r^{332} , 137, induction coil IC, 138, 55 jack spring j^1 , plug sleeve p^1 , 139, to receiver OR.

The operator, on ascertaining the number wanted sets up the same on her key set, (Fig. 10), by depressing the key in strip 60 K^1 corresponding to the first digit, that in the strip K^2 corresponding to the second digit, that in the third strip K^3 corresponding to the third digit, and that in the strip K^4 corresponding to the particular ringing generator to be selected, and then actuates

starting key, SK, whereupon starting relay R^{36} (Fig. 9) is energized in series with trunk cut-off relay R^{42} (Fig. 7) through ground, 126, (Fig. 10) key SK, 140, (140 Fig. 9) R^{36} , 141, 111, r^{361} , 109, 588, 107, 70 (107 Fig. 7), R^{42} , 106, 63, r^{151} , 34, battery to ground. Relay R^{42} opens trunk conductors 9-7 and 10-8 at r^{422} and r^{423} , and energizes relay R^{41} through: B, 34, 44, r^{421} , 142, R^{41} , 570, off-normal contacts 569-568 of switch 75 S^5 to ground. Armatures r^{411} and r^{412} connect the control wires 130 and 135 to control relays R^{21} and R^{20} , respectively, while armature r^{413} connects conductor 147 to one terminal of relay R^{41} through contact 146. 80 Starting relay R^{36} (Fig. 9) takes ground off relay R^{33} through 114, at r^{361} , and locks itself through 148, r^{361} and 115 to ground as previously traced. Armature r^{362} connects starting wire 151 to stepping magnet M^{15} 85 through: B, (Fig. 9) 86, 110, 117, M^{15} , 153, r^{351} , 152, r^{363} , starting wire 151, (151 Fig. 10) contact d^{11} to ground; so that said magnet is momentarily energized, stepping switch S^3 forward one step. 90

The first step of switch S^3 brings the wipers ws^3 , ws^{30} and ws^{300} into engagement with the first contact 18² etc. of their respective banks. Wiper arm ws^{30} connects ground to the common wire 405 of key strip K^1 95 (Fig. 10), and relay R^{53} (Fig. 9) is energized by current from B, 86, ws^3 , 18², 401, 402, R^{53} to ground. The actuation of R^{53} connects the tip conductor 131 to the common impulse conductor 403 at r^{531} which 100 completes the circuit of relays R^{21} (Fig. 7) and R^{78} (Fig. 10) in series as follows: B (Fig. 7), 574, resistance r^2 , 573, R^{21} , 174, contact of R^{41} , 130, into Fig. 9, contact 589, 131, contact of R^{53} , 403, into Fig. 10, R^{78} , 103 404, r^{781} to ground.

The windings of relays R^{21} and R^{78} are so adjusted that only the relay R^{21} will actuate in series with the resistance r^2 , the relay R^{78} remaining inactive until said resistance is 105 shunted by closure of the contacts 572. The actuation of relay R^{21} connects the wire 592 to ground thereby energizing clutch magnet M^{24} , which magnet upon actuation operates to cause the clutch members of the normally inactive switch S^5 , to engage which sets the switch to rotating. As soon as the switch moves out of its normal position contact is opened between springs 568-569 and closed between springs 567-568. As the wipers 110 575 sweep over the multiple contacts 572 the shunt around resistance r^2 is alternately closed and opened. When the wipers of S^5 engage the first set of contacts resistance r^2 is shunted through contacts 572, and the increase in current flow causes relay R^{78} to attract its armature r^{781} which closes the circuit of stepping magnet M^{37} of switch S^{14} 115 which steps its wipers around into engagement with their respective first contacts. 120

The opening of contact d^{11} deenergizes the stepping magnet M^{15} of switch S^3 . When the wipers 575 disengage the first multiples of contacts 572 the shunt is removed from around resistance r^2 and the relay R^{78} retracts its armature while relay R^{21} remains energized in the weaker circuit through resistance r^2 . Upon engagement of wipers 575 with the succeeding multiple of contacts 572, the current flow through R^{78} is again increased causing the switch S^{14} to take another step, and so this cycle of operations is repeated until wiper s^{143} of switch S^{14} engages the contact leading to the particular key depressed in the first key strip K' , which in this case would be contact d^2 . A circuit is then completed through relay R^{79} over the following path: B, R^{79} , 406, d^2 , 407, 408, k^2 , 405 into Fig. 9 to ground through wiper ws^{30} of S^3 . The actuation of R^{79} opens the series circuits of R^{21} and R^{78} at r^{791} , closes the circuit of M^{37} through r^{793} to interrupter I, and locks itself to ground by way of contact 409, r^{792} , 410, multiple contacts d^x of S^{14} to ground. R^{21} retracting its armature opens the circuit of clutch magnet M^{24} which deenergizing disengages the clutch members of S^5 , and the switch S^5 comes to rest with its wipers resting on the first set of a group of ten sets of contacts leading to the two hundreds group of connector trunks (Fig. 8). The switch S^{14} continues to be stepped around by the intermittent energization of M^{37} through the interrupter I, until the wiper arms s^{141} , s^{142} , etc., assume the normal position as shown whereupon the locking circuit of R^{79} is opened between contacts d^x and wiper s^{141} , and R^{79} becoming deenergized opens the intermittent circuit of M^{37} at r^{793} . Wiper s^{142} arriving at normal position closes wire 151 to ground through contact d^{11} again energizing stepping magnet M^{15} (Fig. 9), stepping the wipers of S^3 into engagement with the second set of contacts, in a manner as before described. Relay R^{81} is now energized through wire 402^a and contact 2 s^3 and ground is connected through wiper ws^{30} to wire 411 leading to relay R^{80} of Fig. 10. Actuation of R^{80} connects the grounded side of battery to wire 403 through armature r^{801} and wire 412, and completes the circuit of R^{79} through wire 406 and armature r^{802} to ground. R^{79} upon energization starts the switch S^{14} on another semi-rotation in a manner as before described. The actuation of R^{81} connects the sleeve trunk conductor 132 to wire 403, completing the following circuit: ground (Fig. 10) through armature r^{801} of R^{80} , 412, 403 into Fig. 9, contact of R^{81} , 132, contact 590, 135 into Fig. 7, front contact of R^{41} , 199, R^{20} to battery. Actuation of R^{20} removes the ground connection of R^{41} through 576 deenergizing R^{41} if the trunk 15-16 to which the first selector S^5 is now connected is idle.

R^{41} retracting its armatures disconnects wires 130-174 and 135-199 and connects 130-133 and 135-134, and the relay R^{20} is deenergized by the opening of circuit through wire 199. The momentary energization of R^{20} did not affect magnet M^{24} as the armature of R^{20} was deprived of its ground connection, the switch S^5 thus remaining connected with the first set of contacts of the two hundreds group. However, if said trunk is busy, ground potential will exist at the contact 576 and may be traced from thence through wire 147 to the locking armature of R^{41} , so that when the original energizing circuit through wire 570 is opened R^{41} will remain locked to ground through wire 147. M^{24} is energized by current from battery through M^{24} , 592, front contact of R^{20} , 593 to ground by way of wire 147. The switch S^5 thereupon continues to rotate until it engages a set of wipers leading to an idle trunk 15-16 of a connector switch (Fig. 8), whereupon the ground connection through wire 147 is opened at contact 576 thereby deenergizing clutch magnet M^{24} and relay R^{41} . The deenergization of M^{24} causes switch S^5 to come to rest with its contacts bridging the contacts 576, 561 and 560, the upper members of which individually connect to conductors 15, 16 and 200 leading to an idle connector switch (Fig. 8). Relay R^{41} retracting its armatures connects the control wires 130 and 135 to the tip and sleeve conductors 9 and 10 through wires 133 and 134, respectively, in the same manner as before described.

Switch S^{14} (Fig. 10) continues stepping through the operation of magnet M^{37} in circuit with interrupter I, and upon arriving at normal position as indicated again deenergizes R^{79} and causes the switch S^3 to take another step, this time bringing its wipers into engagement with the third set of contacts. At this juncture relay R^{53} is energized through wiper ws^3 and ground is connected through wiper ws^{30} to wire 430 leading to the key strip K^4 . Actuation of R^{53} completes the circuit of relays R^{78} (Fig. 10) and R^{23} (Fig. 8) in series as follows: Battery B (Fig. 8) through R^{23} , 444, armature m^{11} of M^{11} , 585, shunting armature r^{572} of R^{57} , 586, r^{261} , 16 into Fig. 7, contact 560, 9, 133, 130 into Fig. 9, contact 589, tip conductor 131, contact of R^{53} , 403 into Fig. 10, R^{78} , 404 to ground through armature r^{791} of R^{79} . This circuit energizes both relays, the relay R^{78} completing the circuit of M^{37} which in turn steps the switch S^{14} around one step, and the relay R^{23} completing the circuit of M^{11} in the following path: ground at r^{231} through R^{23} to 215, 214, M^{11} , 213, 212, to battery through off-normal contact springs 211-210. Actuation of M^{11} steps the wipers of S^7 around one step, and at the end of its stroke opens the series circuit of relays 130

R²² and R²⁸ at m¹¹. R⁷⁸ deenergizing, deenergizes M³⁷, and the deenergization of R²³ opens the circuit of M¹¹ at r²³¹. M¹¹ retracting its armature at m¹¹ again closes its circuit of R²³ and R⁷⁸ which results in a second energization of M¹¹ and so this cycle of operation is repeated stepping the switches S⁷ and S¹⁴ around in synchronism until the wiper s¹⁴³ of S¹⁴ engages the third contact d³, which opens the series circuit of relays R²³ and R⁷⁸ and sets the switch S¹⁴ to rotating to its normal position as above described. The latter circuit of R⁷⁹ may be traced from B through R⁷⁰, 406, d³, 431, K⁴, 430 into Fig. 15 9 to ground through wiper ws³⁰. The first energization of R²³ (Fig. 8) energizes R²⁴ by current from battery through r²³³, 247, R²⁴, 202, 200 into Fig. 7, contact 576, 147, 593 to ground through contact of R²⁹. R²⁴, 20 upon actuation, locks itself to battery through 249, r²⁴¹, 250, and r²²². The first energization of R²³ also completes the circuit of R²⁷ as follows: B, r²³², 230, R²⁷, 235, contact of R²⁵, 236 to ground by way of wire 25 200. R²⁷, upon actuation, locks itself to battery through 232, r²⁷¹, 233 and r²³¹.

When the wipers of switch S³ step onto their fourth contacts relay R⁸¹ is energized over wire 402^a through wiper ws³ and ground is connected through wiper ws³⁰ to 30 447, leading to the second strip of keys K² (Fig. 10). R⁸¹ upon actuation connects relays R⁷⁸ and R²² in series with the resistance r³ (Fig. 8) in a circuit which may be traced as follows: battery through armature r²⁹¹ (Fig. 8), 233, r²⁷¹, 232, 230, 229, R²², 584, back contact of R⁵⁷, 581, r², 580 back contact of R⁵⁷, 583, r²⁴², 15 into Fig. 7, contact 561, 10, 134, and so on through windings of relay R⁷⁸ (Fig. 10) and armature r²⁵² to ground, as previously traced. Relay R⁷⁸ will not actuate in series with resistance r³, while the relay R²² does actuate, and in so doing, connects ground through armature r²²¹, 240 and 595^a to clutch magnet M²⁵. M²⁵ thereupon energizes and actuates to engage clutch members of connector switch S⁶ which starts to rotate. As soon as S⁶ moves out of its normal position the circuit of magnet M²² is opened at off-normal contacts 210—211, battery is connected to wire 264 through contacts 210—246 and the wire 595^a leading from magnet M²⁵ is connected to wire 596 through contacts 237—238. The 55 connection of battery to wire 264 partially completes the circuit of the shifting relay R⁵⁷ by way of wire 597. As the switch S⁶ continues in its motion its wipers engage and bridge the contacts of the several rows, 60 577—577^a, 578 and 579. Each time a tens contact 577 is closed resistance r³ is shunted and the increase in current flow energizes relay R⁷⁸ (Fig. 10) which results in the intermittent energization of said relay, and

the constant energization of relay R²² during the movement of switch S⁶.

The switches S⁶ and S¹⁴ continue to rotate, the switch S¹⁴ stepping its wipers around one step each time one of the contacts 577 is closed by the wipers of switch S⁶ so that the wipers of both switches will engage contacts of the same ordinal at the same time. When the wiper arm s¹⁴³ engages the fourth contact d⁴, relay R⁷⁹ is again energized, this time through conductor 447, contacts of key k⁴ and contact d⁴, and again locks itself and closes the actuating circuit of switch S¹⁴ through the interrupter I thereby causing the switch to continue stepping to its normal position. 75 The attraction of armature r²⁹¹ of R⁷⁹ opens the series circuit of relays R⁷⁸ and R²² (Fig. 8), and the latter relay upon deenergization opens the circuit of clutch magnet M²⁵ at r²²¹ which brings the connector switch S⁶ to 80 rest with its wipers in engagement with the first set of contacts in the fourth tens group of the two-hundreds group. During the energization of R²² the locking circuit of R²⁴ was opened at r²²², and the deenergization of R²⁴ connected grounded pole of battery to wire 598. The deenergization of R²² therefore completes the circuit of R⁵⁷, which circuit may be traced as follows: battery through contacts 210—246 of the 85 off-normal springs of S⁶, 264, 597, R⁵⁷, 599, r²²⁴, 598 to ground through contact of R²⁴. Actuation of R⁵⁷ shifts the connection of wires 580 and 581 from 583 and 584 to 585 and 586, respectively, connects wire 581^a to wire 585, removes the shunt from wires 585, 586 through r²⁷², and completes the circuit of R⁵⁸ through a front contact. Circuit of R⁵⁸ may be traced as follows: battery through off-normal springs 210—246, wire 264, 597, 595, R⁵⁸, 594, contact of R⁵⁷ to ground. Actuation of R⁵⁸ opens the circuit through conductor 240 and locks itself to ground. Switch S³ now takes its fifth step bringing its wipers into engagement with 90 the fifth contacts of their respective rows which energizes R⁵² through wire 450 and wiper ws³ and connects ground through wiper ws³⁰ and its fifth contact to wire 600 leading to the third key strip K³. Relay R⁷⁸ is now 95 connected in series with relay R²³ and the resistance r³ as follows: B (Fig. 8), R²³, 444, m¹¹, 585, front contact of R⁵⁷, 580, r², 581, front contact of R⁵⁷, 586, contact r²⁶¹, 16 into Fig. 7, and thence from the tip control circuit of Figs. 7 and 9 as previously traced through R⁷⁸ (Fig. 10), 404, r²⁹¹ to ground. As one of the contacts 577 is already closed by the wipers of S⁶ the resistance r³ is shunted out of the series circuit of relays R⁷⁸ and R²³, giving the maximum current flow which energizes both relays. R⁷⁸ energizing, causing the switch S¹⁴ to take one 100

step, and R^{23} , energizing completes the circuit from ground through r^{231} of R^{23} , 215, r^{232} , 596, contacts 238-237, 595 through clutch magnet M^{25} to battery. The actuation of M^{25} again starts the switch S^3 to rotating which in passing from contact 577 momentarily removes the shunt from around r^3 thus diminishing the current flow which while maintaining the energization of R^{23} 10 causes R^{78} to retract its armature and de-energize M^{37} . Upon closure of the next contact 577 a , R^{78} is again energized this time the shunt circuit being from conductor 580 through contact 577 a , over conductor 581 a and 15 through armature r^{572} of R^{57} , to conductor 585, the second energization of R^{78} , starting S^{14} around another step, and so on until wiper s^{148} engages contact d^6 . R^{79} is now energized by current from ground through wiper 20 ws^{30} , of S^3 through wire 600, contacts of key k^6 and contact d^6 , and upon actuation again locks itself and starts the switch S^{14} to restoring to its normal position. Actuation of R^{79} also opens the series circuits R^{78} and 25 R^{23} at r^{701} and R^{23} retracting its armatures opens the circuit of the clutch magnet M^{26} at r^{231} . It is to be noted here that upon the actuation of R^{23} , that R^{24} is again energized through armature r^{233} , locking itself 30 through r^{222} of R^{22} and removing ground from wire 598 to which ground was previously connected through a front contact of R^{23} . The deenergization of R^{23} removes ground from wire 598 which opens the circuit of R^{57} , which in turn opens the energizing circuit of R^{58} , the latter relay, remaining locked through a front contact. 35 Just before the switch S^{14} resumes its normal position the wiper s^{142} engaging contact d^{12} completes a circuit from ground through d^{12} , 451 into Fig. 9, front contact of R^{82} , sleeve conductor 132 and thence over the sleeve control circuit through Fig. 7 into Fig. 8 and through windings of R^{22} to 45 ground over the same path as previously traced for said relay. The actuation of R^{22} , this time, does not affect clutch magnet M^{25} as the circuit through conductor 240 is maintained open by the locked relay R^{58} . Attraction of armature r^{222} opens the locking circuit of R^{24} , and the attraction of r^{223} completes the test circuit so that if the called line is busy, battery potential existing at its sleeve contact 578 will cause the energization 50 of test relay R^{29} by current over the following path: contact 578, sleeve conductor 18, r^{281} , 252, r^{223} , 251, R^{29} , 201 to ground by way of wire 200. R^{29} upon actuation locks itself to battery through r^{291} , connects the 55 busy back circuit B^2 to the sleeve conductor 16, and completes the circuit of release relay R^{56} . Circuit of R^{56} may be traced from armature r^{291} , 267, 269, R^{56} to ground. R^{56} upon actuation locks itself through r^{561} , wire

601, 264, off-normal springs 246-210 to battery and completes the circuit of M^{25} to ground by way of 595, off-normal contacts 237-238, wire 602, contact of R^{56} to ground. Actuation of M^{25} causes the switch S^6 to continue to rotate until it reaches normal position as shown whereupon the off-normal contacts 237-238 are opened deenergizing M^{25} and allowing the switch to come to rest in its normal position. The busy test potential at contact 578 may be traced to battery as follows: Upper member of 578 through the multiple of 578 engaged by the wiper of a previously connected switch, and thence through the circuits of said switch by way of sleeve conductor 18, 253, r^{281} , 252, back contact of r^{223} , 259, R^{26} , 261, 250, r^{222} to battery. 70

After the test impulse relay R^{22} is deenergized, and completes the restoring circuit of switch S^7 through: B, r^{222} , 250, r^{241} , 85 261, 270, r^{273} , 271, r^{251} , 212, 213, M^{11} , 214, 215, r^{272} , 272, ws^{700} , s^{700} , 274, I to ground.

Magnet M^{11} is intermittently energized until switch S^7 reaches normal position when its circuit is opened between ws^{700} and s^{700} . 90 The test relay R^{29} remains locked, holding busy-back B^2 on trunk conductor 16, to signal the calling subscriber (Fig. 6), who then hangs up his receiver, opening circuit of R^{14} (Fig. 7) which energizes release relays R^{54} 95 and R^{55} in a circuit from ground at off-normal contact 568 through 567, 595, contact of R^{14} , 571, R^{54} and R^{55} in multiple to battery B. The switch S^5 in restoring opens the circuit of R^{29} (Fig. 8) at the test contact 576 thus disconnecting the busy-back. 100

Immediately after the test impulse, the switch S^{14} arrives at its normal or zero position, and wiper s^{142} engaging contact d^{11} , sends an impulse over wire 151, stepping switch S^3 (Fig. 5) forward one step bringing its wipers onto the sixth contact set. When ws^{300} engages contact $6s^{300}$, the restoring relay R^{35} is energized through: B, 86, 110, 166, $6s^{300}$ to $9s^{300}$, ws^{300} , 164, R^{35} to 110 ground. Relay R^{35} opens circuit of R^{36} and R^{42} (Figs. 5 and 3 respectively), at r^{351} and r^{352} , while r^{353} connects magnet M^{15} for intermittent energization through: B, 86, 110, 117, M^{15} , 153, 165, I to ground. Magnet M^{15} steps switch S^3 forward, holding R^{35} energized through ws^{300} and contacts $6s^{300}$ to $9s^{300}$, until the wipers have reached normal position, as shown. The secondary selector switch S^6 is restored by the cam on the 120 switch S^3 , in passing, and the operator's circuit is ready to receive another call.

Assuming that the called subscriber is not busy R^{22} upon energization by the test impulse opens locking circuit of R^{24} which 125 in turn partially closes the circuit of the ringing relay R^{28} at r^{242} . At the end of the test impulse R^{22} retracting its armatures

- completes a circuit for the intermittent energization of ringing relay R^{28} as follows: B, through r^{222} , 250, r^{241} , 261, r^{273} , 277, r^{242} , 278, R^{28} to ground through interrupter I.
- 5 Simultaneously with the energization of ringing relay R^{28} battery supply or trunk cut-off relay R^{26} is energized in series with cut-off relay R^{42} (Fig. 11) in the following circuit: battery B to wire 261 as above traced and thence through R^{26} , 259, r^{223} , 252, r^{281} , 253, 18, 578, 255 into Fig. 11, R^{42} to ground. Energization of R^{42} connects the extensions 254 and 255 to line wires 256 and 257 at r^{431} and r^{432} , respectively. Each 15 actuation of R^{28} disconnects the tip and sleeve branch wires 281 and 253 from wires 287 and 252, respectively, and connects them across the terminals of generator G^3 so that generator current is now sent over the line 20 in the following path: generator G^3 through 279, 38⁷⁰, w_8^{70} , 280, r^{282} , 281, 17, 579, 254 into Fig. 11, contacts of cut-off relay R^{42} , through ringer Q³ at substation A³, back by way of lower contact of R^{42} , 255 into Fig. 8, 578, 18, 25 253, r^{281} , 284, 285, through battery and ground to generator G^3 . During ringing the cut-off relay R^{42} is held energized by connection to battery through resistance r^4 included in the ringing circuit. When the 30 called subscriber lifts his receiver during a non-ringing interval, the tip relay R^{25} is energized by current over the following path: battery through sleeve relay R^{26} to extension 255 (Fig. 11) as previously traced, 35 thence through r^{432} , 257, 283, switch hook H³⁰, R³⁰, T³, 256; r^{431} , 254 into Fig. 8, 579, 17, 281, 287, R^{26} , r^{242} , 275, r^{221} to ground. Actuation of R^{28} disconnects wires 235 and 236 thereby deenergizing R^{27} which in turn 40 opens the circuit of ringing relay r^{273} . The circuit above traced for R^{25} is the battery supply circuit for the called substation. Subscribers A' and A³ are now connected for conversation over the circuit indicated 45 in heavy lines in Figs. 6, 7, 8 and 11.
- At the end of the conversation subscriber at substation A', hanging up his receiver, releases the circuits in the manner as before described.
50. The operation of my system in combination with the system of primary and secondary selection shown in Figs. 12, 13 and 14 is as follows: The subscriber at station A desiring a connection lifts receiver R from hook H which bridges his telephone across line wires 1-2, energizing relays R^1 and R^2 by way of B, 19, 20, R^1 , 21, R^1 , 22, R^{21} , I, station A, 2, r^{42} , 23, ground to battery. Relay R^1 locks to ground through r^{11} , 24, and 55 r^{22} , and connects ground to individual test contact c^{25} through 25 and r^{12} , while R^2 connects ground to row test contact c^{26} through 26 and r^{31} and completes circuit of group lamp L and relay R^4 the former from B, 19, 27, L, 28, r^{32} , ground to battery, the lat- 60 ter from B, 19, 29, R⁴, 30, r^{33} , to ground. Lamp L lights, and relay R^4 completes circuit of stepping magnet M to interrupter I for intermittent energization over the path B, 19, M, 31, r^{42} , 32, r^{11} , 33, I to ground. Magnet M moves switch S step by step until wiper w_8 engages a contact s connected to relay R^{11} (Fig. 13) of an idle primary selector trunk, whereupon relays R^8 and R^{11} (Figs. 12 and 13), are energized by current through B (Fig. 13), 34, 35, 36, r^{131} , 37, R^{11} , 38, (38 Fig 12), s, w_8 , 39, R^5 , 40, r^{42} , to ground. Relay R^5 opens circuit of magnet M at r^{52} , locks itself to ground through r^{51} and completes circuit of R^{11} over path B, 19, 41, R^{11} , 42, R^{52} and ground. Relay R^{11} locks itself to battery through r^{131} , 43, r^{421} , 44, and 34 to B; connects battery to one terminal of relay R^{12} , through 34, 35, r^{133} , 45, 46, r^{152} , 47, and 48; and also completes 45 circuit of rotary relay R^{18} through r^{152} and interrupter I, so that this relay is energized intermittently its circuit being: B, 34, 35, r^{133} , 45, 46, r^{152} , 47, 49, 50, R^{18} , 51, r^{121} , 52, r^{132} , I to ground. At each actuation of relay R^{18} magnet M⁵ is energized by current from B, 34, 57, contacts 58 of foot step switch F⁴, 59, M⁵, 53, r^{131} , ground, stepping primary selector switch S⁴ around until wiper w^{26} engages row test contact c^{26} 50 whereupon relay R^{12} is energized over circuit B (Fig. 13), 34, 35, r^{133} , 45, 46, r^{152} , 47, 48, R^{12} , 49, w^{26} , c^{26} (Fig. 12), 26, r^{21} , ground to battery. Relay R^{12} locks itself to ground through r^{122} , connects test wiper w^{25} to sleeve relay R^{15} through 54, r^{123} and 55, and shifts interrupter I from rotary relay R^{18} to vertical relay R^{19} at r^{121} , so that R^{19} is intermittently energized over the circuit: B, 34, 35, r^{133} , 45, 46, r^{152} , 47, 49, R^{19} , 56, r^{121} , 52, r^{111} , I 100 ground to battery. At each actuation of relay R^{19} vertical magnet M⁶ is energized over the path B, 34, 60, M⁶, 61, r^{161} to ground, stepping switch S⁴ up until wiper w^{25} engages individual test contact c^{25} (Fig. 12) 105 whereupon sleeve relay R^{15} is energized over the circuit: B (Fig. 13), 34, 35, 62, R^{15} , 55, r^{123} , 54, w^{25} , c^{25} (Fig. 12), 25, r^{21} (of relay R^1), ground to battery. Relay R^{15} connects battery to trunk conductor 7, by way of 110 r^{151} , 63, 64, r^{141} , 65, and resistance r, and at the same time opens the circuit of relay R^{12} at r^{122} . Relay R^{12} opens circuit of vertical relay R^{19} and magnet M⁶ is deenergized, which permits wiper w^{25} to stop on contact 115 c^{25} , wipers w^1 and w^4 engaging contacts c^1 and c^4 , respectively. Tip relay R^{14} is now energized through subscriber's telephone in series with R^1 . Simultaneously with the selection of the calling line as described, distributing switch S² (Fig. 12), is stepped around in search of an idle secondary selector, by magnet M⁶ in circuit: B, 19, 41, 66, 67, 68, r^{21} , 69, M⁶, 70, r^{111} , 71, I to ground. Switch S² continues to step around until 120

11

wiper arm w_8^{200} engages a contact s^{200} connected to an idle secondary selector, whereupon relays R^{10} and R^{32} (Figs. 12 and 14) are energized in series, the circuit being: B (Fig. 14), 86, springs 73—74 of operator's jack J, 75, springs 76—77 of foot step switch F⁸, 78, R³², 79, through Fig. 13 into Fig. 12, s^{200} , w^{200} , 80, 81, R¹⁰, 82, r^{112} to ground. The actuation of relay R^{10} causes the energization of relay R^9 , the circuit being: B, 19, 41, 66, 67, r^{101} , 83, 84, R⁹, 85, r^{113} , to ground. Relay R^9 locks itself to battery through r^{92} , and opens circuit of magnet M² at r^{91} , whereupon switch S² comes to rest with wiper arms w_8^2 , w_8^{20} and w_8^{200} resting on contacts s^2 , s^{20} and s^{200} , respectively.

The attraction of armature r^{91} of relay R^9 connects battery to wire 99, which completes part of the row test circuit, and the attraction of armature r^{93} completes the circuit of relay R^8 as follows: B to R⁸, 223, r^{93} to ground. Relay R⁸ grounds wire 80, shunting relay R^{10} out of series with relay R^{32} (Fig. 14), the circuit of the latter relay now going direct to ground by way of wire 80 and armature r^{82} . Relay R^{32} (Fig. 14) completes the circuit of rotary relay R^{39} through interrupter I, so that said relay is intermittently energized by current over B, 86, 87, 30 r^{301} , 88, r^{311} , 89, R³⁹, 90, r^{321} , I to ground. Relay R^{32} also connects one terminal of relay R^{30} to ground through 91 and r^{322} , and locks itself to battery through 92, r^{323} , 93, r^{302} , 87, 86, B. Each actuation of relay R^{39} energizes rotary magnet M¹³ through B, 86, 94, M¹³, 95, r^{301} to ground. Magnet M¹³ steps switch S⁸ around until wiper w_8^{82} engages contact s^{82} . The first rotary step of the switch S⁸ disconnects contacts 76 and 77 40 of switch F⁸ and connects contacts 76 and 290, which opens the initial energizing circuit of relay R^{32} , (that relay, however, remaining energized through its locking circuit), and closes the circuit of off-normal lamp L⁷ as follows: B, 86, 73, 74, 75, 76, 290, L⁷ to ground. When wiper w_8^{82} engages contact s^{82} the relay R^{31} is energized over the path: B, ground to r^{322} (of relay R^{32}), 91, 96, R³¹, 97, w_8^{82} , s^{82} , 98, through Fig. 3 into Fig. 2, s^{20} (in switch S²), w_8^{20} , 99, r^{91} , 68, 67, 66, 41, 19, battery. Relay R^{31} locks itself to battery through: 100, r^{312} , 101, 88, r^{301} , 87, and 86, opens circuit of relay R^{39} and closes circuit of relay R^{40} at r^{311} . Relay 55 R^{39} opens circuit of magnet M¹³ at r^{391} , which stops switch S⁸ with wiper w_8^{82} engaging contact s^{82} . As circuit of relay R^{40} is completed at r^{311} said relay is intermittently energized through: B, 86, 87, r^{301} , 88, 60 r^{311} , 102, R⁴⁰, 103, 90, r^{321} , I, ground. Each actuation of relay R^{40} energizes vertical magnet M¹⁴ through: B, 86, M¹⁴, 104, r^{401} , ground. Magnet M¹⁴ steps switch S⁸ up until wiper w_8^{84} engages contact s^{84} , whereupon relay R^{30} is energized through: B,

ground to r^{322} (relay R^{32}), 91, R³⁰, 105, w_8^{84} , s^{84} , 45 (45, Fig. 13), r^{133} , 35, 34, battery. Relay R^{30} opens locking circuit of relay R^{32} at r^{302} , also opens circuit of relay R^{40} at r^{301} . r^{401} of relay R^{40} opens circuit of vertical magnet M¹⁴, which stops switch S⁸ with wipers w_8^{80} , w_8^{81} , w_8^{83} and w_8^{84} on contacts s^{80} , s^{81} , s^{83} and s^{84} . (Wiper w_8^{82} is raised off row contacts by first step). Wiper w_8^{83} engaging contact s^{83} , (Fig. 14) relays R³⁴ and R⁴², 75 (Figs. 14 and 13) are energized through: B, (Fig. 3), 34, 35, 36, r^{151} , 63, 106, R⁴², 107, (107 Fig. 14), s^{83} , w_8^{83} , 108, r^{313} , 109, r^{331} , 111, 112, R⁴², 113, r^{331} , 114, r^{301} , 115, r^{352} , 116, r^{322} , ground. 80

Relay R⁴², when actuated, opens series circuit of relays R⁵ and R¹³ (Figs. 12 and 13) at r^{421} . Relay R¹³ disconnects interrupter I at r^{132} and relay R⁵ (Fig. 12) opens circuit of relay R¹¹ at r^{53} . Relay R¹¹ deenergizing 85 opens circuits of magnet M², relay R⁹ and relay R¹⁰, while relay R⁸, its circuit opened at r^{93} , opens circuit of stepping magnet M¹ at r^{81} . This prepares distributing switches, S and S², with their relays, for another call. 90 Relay R³⁴ becoming energized closes circuit of night alarm N through: B, 86, 110, 117, 118, r^{341} , 119, N, to ground; closes circuit of guard lamp L² (Fig. 10) through B (Fig. 5), 86, 110, 117, 118, r^{342} , 120, 121 (121 Fig. 95 10), L² to ground; closes circuit of service meter E (Fig. 14) through B, armature r^{343} , 122, 242, and magnet of service meter E to ground; and line lamp L³ (Fig. 10) through B (Fig. 14) r^{343} , 122, 123 (123 Fig. 10), L³ 100 to ground. The operator, perceiving the signal, depresses listening key LK (Fig. 10) energizing listening relay R³³ (Fig. 14) through: b (Fig. 14), 86, 87, r^{301} , 88, 101, r^{312} , 124, R³³, 125 (125 Fig. 10), contacts of key LK, 126 to ground. Relay R³³ energizing, opens series circuit of relays R³⁴ and R⁴² at r^{331} and locks itself to ground through r^{331} , and 114, as previously traced. Relay 105 R⁴² deenergizing, opens circuit of relay R⁴¹ 110 at r^{421} . Relay R³³ completes the operator's listening circuit as follows: receiver OR, 127, plug P, tip p, spring j, 128, r^{333} , 129, 131, w_8^{80} , s^{80} , 130 (130 Fig. 13), r^{411} , 133, 9, 422, 7, condenser C¹, 5, w_8^3 , c^3 , (Fig. 12), 3, r^{21} , line wire I, subscriber's telephone, line wire 2, r^{22} , 4, c^4 , w_8^4 , (Fig. 13), 6, condenser C², 8, r^{423} , 10, 134, r^{312} , 135 (135 Fig. 14), s^{81} , w_8^{81} , 132, 136, r^{332} , 137, coil IC, 138, jack 120 spring j¹, plug sleeve p¹, 139, receiver OR. 125

From this point on the operation is the same as that first described, inasmuch as the circuits involved in both are identical.

At the bottom of Fig. 12 I have shown a switch S', having contacts s' and a selector arm ws' . This switch is actuated by a magnet M' which in turn is energized by a time controlled element d¹¹. This switch forms a part of the complete apparatus disclosed in my prior application Serial No. 611,923, 125 130

filed March 2, 1911, and is illustrated herein for the sake of completeness. As it forms no part of the present invention, and is fully described in the said prior application, I have deemed it unnecessary to describe it specifically herein. Speaking generally, the function of this switch is to guard against the accidental connection of a calling line to an inoperative circuit or switch. It acts to forward the line to another circuit or another switch if the first connection initiated has not been completed within a predetermined time.

I claim—

1. In a telephone exchange system, a central station, substations, substation lines having terminals in the central station, primary selector switches adapted to seek and find calling lines, first selector switches connected therewith, and connecting links and switches adapted to complete the connection between the said first selectors and called lines, said selector and connector switches being of the mechanically driven type but having primary and secondary movements whereby the group of lines or links may first be picked out and thereafter the individual line or link of the group, and an operator's sending machine connected with the first selector switches and directly controlling the primary movement of the first selector switches, and both the primary and the secondary movement of the connector switches, together with a testing relay controlling the secondary movement of the selector switch.

2. In a telephone exchange system, subscribers' lines and means to interconnect the same comprising a plurality of links and mechanically driven switches, said switches having both primary and secondary movements in a single determinate plane, a manually set impulse operated device to determine the extent of primary movement of the switch, driving means for said device having a circuit closed during the period of said primary movement, and means connected with the switch to produce variations of the current in the circuit of said driving means.

3. In a telephone exchange system, subscribers' lines, means for interconnecting the same comprising links and mechanically driven selector switches, step by step selective means manually set and operated from the switches to determine the extent of movement of the same, actuating means for said selective device the circuit of which is closed during the period of movement of the switch, a switch control magnet in said circuit, and means connected with said switch and operated during the movement thereof to vary the current in said circuit.

4. In a telephone exchange system, subscribers' lines, means to interconnect the same comprising links and mechanically driven selector switches, a manually set step

by step device adapted to be actuated from the switches to determine the extent of movement thereof in accordance with the manual setting, an actuating magnet for said device and a control magnet for the switch in a series circuit closed during the period of connective movement of the switch, said control magnet of the switch being responsive to smaller current flow than said actuating magnet, and means connected with the switch to increase the flow of current in said circuit at determinate intervals during its movement.

5. In a telephone exchange system, subscribers' lines, means for interconnecting the same comprising links and mechanically driven selector switches and control relays therefor, an impulse operated device and control relay therefor, said control relays being energized in series in a single circuit, a circuit changing device associated with each of said switches, adapted to be included in said series circuit and a circuit changing device operated by said impulse operated device also included in said series circuit, the control relay of the impulse operated device being responsive to both of said circuit changing devices and the said switch control relay being responsive only to the circuit changing device operated by the impulse operated device.

6. In a telephone exchange system, subscriber's lines and means for interconnecting the same comprising links and mechanically driven selector switches, a control relay for each of said switches, an impulse operated device, a control relay for said operated device, a circuit changing means associated with each of said selector switches and operated in the movement of its switch, circuit changing means associated with the impulse operated device and operated thereby and a single series circuit including said control relays and circuit changing means, the switch control relay being responsive to the circuit changing means of the impulse operated device and the control relay of the impulse operated device being responsive to the circuit changing means of the switch.

7. In a telephone exchange system, subscribers' lines, means for interconnecting the same comprising links and mechanically driven selector switches, a control relay for each of said switches, means for producing variation in current strength associated with each switch and operated in the movement thereof, an impulse operated device, a control relay for said impulse operated device, circuit interrupting means operated in the movement of said impulse operated device and a single series circuit including the circuit interrupting device, the control relay of the impulse operated device and the control relay and current changing means of one of said switches, the control relay of the

impulse operated device being responsive to the variations in current strength produced by the current varying means of the switch and the switch control relay being responsive only to a completion and interruption of the series circuit.

8. In a telephone exchange system, subscribers' lines and means for interconnecting the same comprising links and movable selector switches with separate mechanical means for driving the same, an impulse operated device, a stationary control relay for each of said switches, means responsive to said relay controlling said driving means, a control relay for said operating device, a single series circuit including the control relay of said impulse operated device and one of said switch control relays, means operated in the movement of said switch for indeterminately controlling only the operating relay of the impulse operated device over said series circuit and means operated in the movement of said impulse operating device to determinately control said switch control relay over said series circuit.

9. In a telephone exchange system, subscribers' lines and means for interconnecting the same comprising links and mechanically driven switches, said switches having both primary and secondary movements, each of said switches having a primary relay for controlling the primary movement and a secondary relay for controlling the secondary movement, a series circuit, an impulse operated device responsive to current changes in said series circuit, a circuit changing device associated with each of said switches and operated in the movement thereof to produce

current variations in said series circuit, means for alternately including the control relays of one of said switches in said series circuit and circuit interrupting means operated in the movement of the impulse operated device included in said series circuit.

10. In a telephone exchange system, subscribers' lines, means for interconnecting the same comprising links and selective switches adapted to effect the closure of a series of contacts in two sets or subdivisions, with separate mechanical means to drive said switches, and a primary and secondary control relay for each of said switches, said primary control relay being controlled through the contacts of one set and the secondary relay being controlled through the contacts of the other set.

11. Switching mechanism comprising sets of contacts arranged in groups, a rotatable contact closing device adapted when rotated to successively close said sets of contacts, an operating shaft, an electromagnetic clutch device adapted when operated to connect said contact closing device with the operating shaft, a control relay for said electromagnetic clutch having its circuit controlled through contacts in the first set of each group and another control relay for said electromagnetic clutch having its circuit controlled through other contact sets in all the groups.

In testimony whereof I affix my signature in presence of two witnesses.

EDWARD E. CLEMENT.
